UNITED STATES PATENT OFFICE

CONSTANT ARMIN EGLI, OF WEEHAWKEN, NEW JERSEY

DESIGN FOR A LAMP STAND

Application filed April 1, 1931. Serial No. 39,313. Term of patent 3½ years.

To all whom it may concern:

Be it known that I, CONSTANT ARMIN EGLI, a citizen of the United States, residing at Weehawken, in the county of Hudson and State of New Jersey, have invented a new, original, and ornamental Design for a Lamp Stand, of which the following is a specification, reference being had to the accompanying drawings, forming part thereof.

Fig. 1 is a side elevation; Fig. 2 is a front elevation, and Fig. 3 is a plan view of the base forming part of the design shown in Figs. 1 and 2 of a lamp stand showing my new design.

I claim:

The ornamental design for a lamp stand, as shown.

CONSTANT A. EGLI.
